FIG. 1 is a first perspective view of an electronic fuel injection throttle body design;

FIG. 2 is a second perspective of the design of FIG. 1;

FIG. 3 is a front view of the design of FIG. 1;

FIG. 4 is a rear view of the design of FIG. 1;

FIG. 5 is a top view of the design of FIG. 1;

FIG. 6 is a bottom view of the design of FIG. 1;

FIG. 7 is a right side of the design of FIG. 1; and,

FIG. 8 is a left side view of the design of FIG. 1.

The broken lines shown in the drawings are included for the purpose of illustrating the unclaimed boundary and unclaimed portions of the electronic fuel injection throttle body. The broken lines form no part of the claimed design.
